UNITED STATES PATENT OFFICE.

ERNEST L. DAHLFUES, OF SAN DIEGO, CALIFORNIA.

SHOE-CLEANER.

955,769.

Specification of Letters Patent. Patented Apr. 19, 1910.

Application filed April 15, 1909. Serial No. 490,133.

To all whom it may concern:

Be it known that I, ERNEST L. DAHLFUES, a citizen of the United States, residing at San Diego, in the county of San Diego and State of California, have invented certain new and useful Improvements in Shoe-Cleaners, of which the following is a specification.

My invention relates to improvements in shoe cleaners, and has for its objects, to provide simple and efficient means for scraping and cleaning the shoes to free them of mud and dirt, such means being adapted for ready attachment to a door-step, porch or other convenient location and so constructed that the brushes and scraper of said cleaner are easily taken out and others installed when it is desired to renew either of these parts. I attain these objects by the apparatus illustrated in the accompanying drawing, in which—

Figure 1 is a plan view of my improved shoe cleaner: Fig. 2 a side elevation thereof; and Fig. 3 a cross section on line A—B, Fig. 1.

Similar characters of reference refer to similar parts throughout the several views.

The frame 1, the stand 2, the brushes 3, 4 and 5, the brush retaining bar 6, the scraper 7, and the scraper brackets 8 constitute the parts of my shoe-cleaner.

The frame 1 is made a trifle longer than the brushes 3, 4 and 5 which are common brushes, and said frame is so made as to provide three recesses adapted to fit and envelop the backs of the brushes 3, 4 and 5, the front end 1^a of said recesses being partially closed against which the ends of the brushes set when inserted in said recesses. The brush 3 is wider than the others and is for cleaning the bottom of the soles of the shoes while the others are for cleaning the sides of the soles and shoes. At the back end 1^b, said frame is provided with a brush retaining bar 6, which is provided with holes in each end into which are inserted the bolt portion 8^a of the scraper brackets 8 which hold said bar 6 in place by means of nuts 8^b screwed onto the lower ends of said bolt por-

tions 8^a of said brackets 8, said bolt portions 50 act as supports for the purpose of holding the side brushes 4 and 5 in place while the bar 6 holds the lower brush 3 in place.

The upper and extended portions of the scraper brackets 8 are provided with square 55 holes at 8^c adapted to fit the square ends of the scraper 7, said square ends of the scraper extending through the brackets 8 when the shoe-cleaner is assembled as shown. This shoe-cleaner is provided with a curved 60 bracket stand 2, to which it is fastened at 2^a and said stand may be attached to a porch or steps 2^b where it is desired to place the same: this stand may be of different shape, but I prefer to make it this shape so that the 65 shoe-cleaner may extend out from said porch or steps so as to allow the dirt to drop to the ground below.

It can be readily seen with this construction that by removing the nuts 8^b and then removing the brackets 8, bar 6 will be released and all three of the brushes can then be easily removed and that the scraper brackets and the scraper would be taken off thereby leaving all the parts separate for 75 cleaning.

Having thus described my invention what I claim is:

1. A shoe cleaner, comprising a plurality of brushes, a frame provided with bottom 80 and side recesses adapted to hold said brushes, the flexible portions of said brushes extending upward and inward, extension brackets provided with extension bolts attached to one end of said frame by means 85 of said extension bolts, a scraper on the outer ends of said brackets, a bar provided with holes in each end extending across said frame and attached thereto by means of 90 said bolts and a curved bracket stand for 95 supporting said shoe cleaner all substantially as set forth.

2. A shoe cleaner, comprising three brushes, a frame having a bottom and two side recesses for holding said brushes, the 95 flexible portion of the bottom brush being upward and the side brushes inward, a detachable bar attached to the lower and back

side of said frame adapted to hold said bottom brush in said bottom recess, a scraper, brackets extending upward and backward and carrying said scraper at their outer ends, 5 said brackets being provided with extension bolts set into said frame for holding said side brushes in said side recesses, nuts on said bolts, and a curved bracket stand for

supporting said frame, all substantially as set forth. 10

In testimony whereof I affix my signature in presence of two witnesses.

ERNEST L. DAHLFUES.
